HAIR DRYER

Archer W. Davidson, Jr., Longmeadow, Mass., assignor to Stark Davidson Mfg. Corp., West Springfield, Mass.,
a corporation of Massachusetts

Filed Mar. 13, 1962, Ser. No. 69,244

Term of patent 3½ years

(Cl. D86—10)

FIG. 1 is a perspective view of a hair dryer, showing my new design; and

FIG. 2 is a rear perspective view thereof on a reduced scale taken at a 90 degree angle to that of FIG. 1 with the broken line showing of the tubes omitted for convenience of illustration.

The essential features of my invention are shown in full lines on the drawing.

The present design is symmetrical about a central vertical plane running from front to rear thereof and the side hidden from view is a mirror image of the side opposite thereto.

I claim:

The ornamental design for a hair dryer, substantially as shown and described.
